UNITED STATES PATENT OFFICE.

FREDERICK W. BARNES AND FRANK W. LOVEJOY, OF ROCHESTER, NEW YORK,
ASSIGNORS TO EASTMAN KODAK COMPANY, OF ROCHESTER, NEW YORK, A
CORPORATION OF NEW YORK.

CUT-FILM HOLDER.

1,151,153.

Specification of Letters Patent. Patented Aug. 24, 1915.

Application filed May 13, 1914. Serial No. 838,190.

To all whom it may concern:

Be it known that we, FREDERICK W. BARNES and FRANK W. LOVEJOY, of Rochester, in the county of Monroe and State 5 of New York, have invented certain new and useful Improvements in Cut-Film Holders; and we do hereby declare the following to be a full, clear, and exact description of the same, reference being had to the 10 accompanying drawings, forming a part of this specification, and to the reference-numerals marked thereon.

Our present invention relates to photography and more particularly to handling devices for cut film sheets during the developing, fixing, washing and drying thereof, or such other treatments as it is desired to subject the films to, and the invention has for its object to provide a simple, light, cheap 20 and efficient holding frame for the films that will be convenient to use and which will adequately protect them during the operations mentioned while still exposing them entirely to the action of the baths or the 25 drying agents.

To these and other ends the invention consists in certain improvements and combinations of parts all as will be hereinafter more fully described, the novel features being 30 pointed out in the claims at the end of the specification.

In the drawings: Figure 1 is a front elevation of a cut film holder constructed in accordance with and illustrating one embodiment of our invention, a film being 35 shown in place therein, and Fig. 2 is a bottom end view of the wire frame, the holding clips and film being shown in section along the line 2—2, Fig. 1.

Similar reference numerals throughout the several figures indicate the same parts.

While the device of our invention is suitable for application to the handling of any flexible photographic sheet, it is especially 45 designed to accommodate the cut films or flexible flat sensitized sheets of the larger sizes, now quite generally used for portrait work, during the operations before mentioned. To these ends, we provide, in the 50 practice of our invention, a flat frame that may be conveniently and cheaply formed from a substantially continuous length of round wire, as shown. It is rectangular in general shape and comprises upper and

lower end rails 1 and 2, respectively, and 55 side rails 3. The upper end rail 1 is doubled upon itself at each end to constitute laterally projecting supporting arms 4 that may be laid upon suitable parallel supports B to suspend the frame and its contents either 60 in the bath or while being dried in the air. The same rail may be further provided at a central point with an eye 5 having extended therefrom a laterally offset hook 6 as an additional means for suspending the 65 frame from a nail, a line or other similar support.

At each corner of the frame, each rail is bent inwardly at 7 in advance of its juncture with the adjoining rail to form a jog or 70 reversed corner and on the said portion 7 of one such two adjoining rails (in the present instance, the side rail) is mounted, in each instance, a film holding device. The latter; we prefer to have comprise a spring 75 clip of the type shown embodying a fixed jaw 8 soldered or otherwise fastened to the portion 7 and carrying a pintle 9 and a movable jaw 10 working in opposition thereto on the pintle 9, the jaws being normally held closed together by a spring 11 80 surrounding the pintle. They are opened by simply pressing down upon the operating portion 12 of the upper jaw and may thus be made to grasp or to release the sheet, at 85 will, as the case may be.

The film sheet to be treated is indicated at A and the frame is made of such a size with relation thereto that the clips may be engaged at the extreme corners thereof in 90 the manner shown and the sheet securely held taut in flat condition with both of its sides fully exposed to whatever agents, liquid or gaseous, to which it is desired to expose it. While in the developing, fixing or 95 washing tanks, the frame will preferably be suspended from the supporting rods B.

It will be observed that the inwardly turned portions 7 of the rails give extended lengthwise support to the clips 8—10 while 100 the rails themselves are spaced outwardly from the edges of the sheet A and protect the latter from contact with the sides of the vessel containing the bath and from other bodies.

We claim as our invention:

1. An article of the character described comprising an open frame having a plu-

rality of sheet holding devices arranged in spaced relation thereon and composed of a rod or wire doubled upon itself at opposite corners near one end to form laterally projecting supporting arms from which the frame is adapted to be suspended.

2. An article of the character described comprising an open frame having one of two adjacent rails turned inwardly in advance of its junction with the other rail and a sheet holding device mounted on said inwardly turned portion for the purpose set forth.

3. An article of the character described comprising an open rectangular frame com-

posed of bent wire and having an inwardly turned jog at each corner and a sheet holding clip at each corner of the frame comprising a fixed jaw secured upon an inwardly turned portion and a movable jaw 20 coöperating with the fixed jaw in such position that the rails of the frame project beyond a film sheet held at its corners by the clips.

FREDERICK W. BARNES.
FRANK W. LOVEJOY.
